UNITED STATES PATENT OFFICE.

PAUL KAMINSKI, OF SPANDAU, NEAR BERLIN, GERMANY, ASSIGNOR TO SIEMENS UND HALSKE AKTIENGESELLSCHAFT, OF BERLIN, GERMANY, A CORPORATION OF GERMANY.

SIGNALING SYSTEM, PARTICULARLY FOR ARTILLERY PURPOSES.

1,124,913.

Specification of Letters Patent. Patented Jan. 12, 1915.

Application filed May 20, 1911. Serial No. 628,429.

To all whom it may concern:

Be it known that I, PAUL KAMINSKI, a subject of the German Emperor, and residing at Spandau, near Berlin, Germany, have 5 invented certain new and useful Improvements in Signaling Systems, Particularly for Artillery Purposes, of which the following is a specification.

My invention relates to signaling systems 10 particularly adapted for artillery purposes.

A primary object of my invention is to solve the problem of causing two coacting transmitters to move through different distances when the one is driven by the other.

15 To this end I provide between the two transmitters an intermediate gear which coöperates with the devices in such manner that the driven transmitter is moved at a speed different from the transmitter driving the former.

20 I prefer to arrange the intermediate gear in a manner known in itself so that it engages only in certain positions with the transmitter system which is to be driven, but otherwise enables the same to move perfectly independently. Finally I make both 25 transmitters as well as the intermediate gear rotatable clockwise and counter-clockwise.

An embodiment of the invention is represented in the accompanying drawings, which 30 show two successively coöoperating transmitters. The receivers having no bearing on the present invention, have been omitted in the drawings.

In said drawings,—Figure 1 is an elevation 35 of the apparatus; Fig. 2 is a plan view thereof, the cover being removed and only the mechanical features of the device being shown, with one disk partly broken away.

The electrical features of the device do not 40 form a part of the present invention. Any suitable means may be employed by which signals are transmitted synchronously to the receivers which are not shown here, by operating the handle of one or the other of 45 the two transmitters.

Referring now to the construction of the device, the two transmitters consist of the armatures $a-a_1$, mounted on shafts k, k' respectively, which may be operated for instance by handles f and i respectively. The 50 armatures a, a' , when set into different angular positions by the above handles, send current to the receivers in a manner well known in the art, so that the description of

this portion of the apparatus has been omitted. On the shafts k and k_1 of the two armatures are mounted signal disks b, b_1 respectively, which are of equal size and which bear on their upper faces either signals or signal characters, according to the purpose 55 for which the device is intended. These characters may be observed through suitable windows (not shown) provided in the face plate t of the casing which contains the entire apparatus. The signal disk b may be 60 for instance provided with figures and as an example with 21 fields, each representing one figure. Disk b_1 may be only provided with 11 fields, each having one numeral 65 from one to eleven. Accordingly, when the disk b is in a definite position and the disk b_1 is to be rotated one division by the former disk moving from one division to the next, it is necessary to rotate the disk b_1 a greater 70 distance than corresponds to one division of the disk b . To this end, according to my invention I arrange between the two transmitter systems an intermediate gear c which 75 on the one hand can coact with the tappet d fast on the axle k of the one transmitter system a and, on the other hand, can simultaneously mesh with the gear e on the axle k_1 of the second transmitter system a_1 . Accordingly, when the disk b is rotated by its 80 handle f , into a certain position the intermediate gear c is driven by the tappet d and the gear e and disk b_1 is also rotated. The ratio of transmission between the intermediate gear c and the gear e must be proportioned according to the number of the 85 signals on the disks in each instance and to the consequent different length of path to be traversed when the two systems are rotated together in order to cause the next signal to appear in the window. By this arrangement, the following result is obtained: If at 90 the completion of one revolution of disk d , the latter is moved into the position in which the last of its fields appears before the window, also disk d_1 is moved one entire field or 95 division, though the divisions of disk d_1 are larger than those of disk d .

In order to increase the certainty of action and to bring the intermediate gear after each motion into a position, as shown in the 100 drawing, in which the second transmitter system is able to move freely, I arrange on the shafts of the transmitters and of the in-

termediate gear notched wheels g , g_1 , g_2 , into the notches of which the ends of spring pressed arms h , h_1 , h_2 , respectively, fall. Instead of bearing numbers the disk b_1 5 may bear different commands, for example, which are transmitted when rotating the transmitter into a position in which the desired command appears in the window.

I claim:—

- 10 1. In a signaling system, the combination with two transmitters, one of the same having a toothed gear, of an intermediate toothed gear meshing with, and having a number of teeth different from the number 15 of teeth of the former toothed gear, means driven by the other transmitter for intermittently driving the said intermediate gear, both transmitters and said intermediate gear being rotatable either clockwise or counter- 20 clockwise, said first named transmitter with its gear wheel being rotatable independently of said intermediate gear wheel in predetermined positions of said intermediate wheel.
- 25 2. In a signaling system, the combination with a transmitter comprising a shaft carrying a toothed gear, of a second transmitter comprising a shaft carrying a tappet, and an intermediate toothed gear adapted 30 to mesh with the former toothed gear, having a number of teeth different from the number of teeth of the former toothed gear, and adapted to be driven intermittently by the said tappet, both transmitters and said 35 intermediate gear being rotatable either clockwise or counterclockwise, said first named transmitter with its gear wheel being rotatable independently of said intermediate gear wheel in predetermined positions of 40 said intermediate wheel.
- 40 3. In a signaling system, the combination with a transmitter comprising a shaft carry-

ing a toothed gear, of a second transmitter comprising a shaft carrying a tappet, an intermediate toothed gear adapted to mesh 45 with the former toothed gear, having a number of teeth different from the number of teeth of the former toothed gear and adapted to be driven intermittently by said tappet, and means for positively setting said 50 toothed gears and the said tappet in predetermined positions, both transmitters and said intermediate gear being rotatable either clockwise or counterclockwise, said first named transmitter with its gear wheel being 55 rotatable independently of said intermediate gear wheel in predetermined positions of said intermediate wheel.

4. In a signaling system, the combination with two transmitters, one of the same having a toothed gear, of an intermediate toothed gear meshing with, and having a number of teeth different from the number of teeth of the former toothed gear, means driven by the other transmitter for intermittently driving the said intermediate gear, said first named transmitter with its gear wheel being rotatable independently of said intermediate gear wheel in predetermined positions of said intermediate 65 wheel, both transmitters and said intermediate gear being rotatable either clockwise or counterclockwise, each of said transmitters having an operating handle of different characteristic form for the purpose of identification. 75

In testimony whereof I have signed my name to this specification in the presence of two witnesses.

PAUL KAMINSKI.
